UNITED STATES PATENT OFFICE

143,537

DESIGN FOR A FLOOR BRUSH

Alfred L. Le Febvre, Windsor, Conn., assignor to The Fuller Brush Company, Hartford, Conn., a corporation of Connecticut

Application March 17, 1945, Serial No. 118,534

Term of patent 14 years

(Cl. D9—2)

To all whom it may concern:

Be it known that I, Alfred L. Le Febvre, a citizen of the United States, and a resident of Windsor, in the county of Hartford and State of Connecticut, have invented a new, original, and ornamental Design for a Floor Brush, of which the following is a specification, reference being had to the accompanying drawing, forming part thereof, in which the figure is a perspective view of a floor brush showing my new design.

The opposite side and end of the brush not shown are substantially like the side and end shown.

I claim:

The ornamental design for a floor brush, as shown and described.

ALFRED L. LE FEBVRE.
